KEY INTERPOSER MEANS IN PRINTING AND PUNCHING MACHINE

Arnold R. Bone, Needham, Mass., assignor to Dennison Manufacturing Company, Framingham, Mass., a corporation of Massachusetts

Filed Mar. 21, 1962, Ser. No. 181,272

4 Claims. (Cl. 101—19)

This invention relates to printing and punching machines adapted to print information and to punch corresponding information which is intended to be "machine read." Reference may be made to the U.S. patent to Bone and Sloan No. 2,890,650 for a description of a printed and punched multiple-section ticket and mechanism for preparing such ticket. That patent gives as an example, the use of such ticket as a price ticket of which one of the sections may be detached at the time of sale of the ticketed article. A further use of tickets of this type is in manufacturing or article-handling generally in which an article or batch is to be subjected to several operations, inspections, counting or the like, and it is desired to have machine-readable records as to the progress of the articles or batches of articles. It would be desirable in such case to form the ticket with sufficient sections so that a section could be detached at each of several stations, for control or statistical purposes.

In such use of printed and punched tickets, it is desirable to provide for printing and punching on the individual ticket section that is detached at any particular station information that is peculiar to the operation at that station, for example, the date, a quantity figure, such as a quantity removed from the batch at that station, or the number of the station or of the operator at that station. Such information printed and punched at a particular station, may be in addition to information which is printed and punched on some or all of the sections of the ticket in the initial manufacture of the ticket.

For such printing and punching of individual ticket sections detached at various stations in the flow of the article, it is important that the device for printing and punching the information that pertains to the operation at that particular station shall be inexpensive, so that many of such devices can be used at many such stations, and shall be easily operated by persons who are not particularly experienced in printing and punching tickets but have other more primary duties. It is moreover important that there shall be no possibility of unintended failure of the printing and punching to correspond. The quality of the punching (to be machine-read), and preferably also the quality of the printing, should be equal to that which is obtainable in initially printing and punching multiple-section tickets by specialized machines and operators.

Where the tickets are initially manufactured with some printing and punching thereon, it is of course to be understood that such original printing and punching need not fill up the whole of each ticket section. By economical use of initial printing and punching, space may be left for the addition of further printing and punching of various other ticket sections at later stages. However, the small size of the ticket section (typically only 1 inch wide and for example in the region of 2 or 3 inches long) imposes a severe limitation on the equipment to be used for any printing and punching if it is desired that these operations are to be performed simultaneously and within the confines of so much of a ticket section area as is available. It will be noted that in the initial manufacture of tickets as in said patent to Bone and Sloan, printing on a given ticket section is performed at one station, and punching is performed at another station, to which the ticket section is automatically fed. That would be undesirable in a ma-

2

chine which was to be operated only occasionally and which must be inexpensive.

It is proposed in the U.S. patent to Rothmann No. 2,943,559 to provide a series of settable marking wheels each comprising a print wheel and a punching wheel, the latter carrying adjacent to each printing numeral on the print wheel one or two punch pins located in the one or two positions of a four-position code which correspond to the number printed by the associated print wheel number character. Printing and code punching are thus interspersed in a direction axially of the series of marker wheels.

I consider it to be preferable to avoid such interspersion of printing and punching in a series of marking wheels for several reasons, among which are (1) in order to reduce the amount by which the space for a row of printing restricts the space available for punch holes; (2) in order to permit easy and accurate alignment of punches with closely fitting die holes in an underlying die; (3) to guide the punches close above the surface of the die and have them retract within holes in a guide positioned close to the die so as to separate the punched ticket and the punches positively and shield the operative ends of the punches which are withdrawn within these holes; (4) in order to permit the punches to be assembled without fixed attachment to a common support but rather with the more usual sliding insertion into holes in retainer plates.

Much of the complication that has been involved in the problem of printing and punching simultaneously within the confines of one small ticket section or a part thereof remaining available after previous printing and punching has apparently resulted from the fact that for the solution of that problem there has been no evident way of preserving both the construction of punching equipment and the general mode of changing of setting of printing and punching that has been customary in initial manufacture of printed and punched tickets. The present invention involved the thought that a different type of change of setting will permit the most advantageous features of punching equipment to be retained, consistently with the printing and punching being performed simultaneously within a small area.

The invention will be explained by a description of a preferred embodiment.

In the accompanying drawings:

FIG. 1 is a side elevation with portions of the machine broken away;

FIG. 1a is a fragmentary view partly in side elevation and partly in vertical section showing the movable head portion of the device of FIG. 1 in its raised position;

FIG. 2 is a front elevation;

FIG. 3 is a vertical sectional view taken on the line 3—3 of FIG. 1a;

The working parts of the machine are supported by a bed plate 10 which may be mounted upon any suitable supporting means, not shown, for example legs, a supporting frame or stand, the whole machine being portable. Pillow blocks 11 and 12 which depend from the bedplate 10 are slotted at 13 and 14 and provide vertical guideways for a shaft 16. The shaft 16, which can move vertically in the slots 13 and 14, constitutes the support for a vertically movable link 20, which extends up through an opening 21 in the bedplate 10 and carries at its upper end a horizontally extending plate 23 which is guided by a stationary vertical stud 24.

Toggle links 25 connect the vertically movable shaft 16 to a swingable lower shaft 26 which is constrained to movement about a stationary intermediate shaft 28 by an H-shaped link 29 (FIG. 2). As indicated in FIG. 1 the toggle links 25 are curved to extend around the stationary shaft 28. An operating lever 30 extending from

link 29 provides for swinging the link 29 to carry the toggle links to the lower full line position of FIG. 1 which draws down the shaft 16, link 20, and its plate 23 to effect the punching and printing. The link 20 and plate 23 carry vertically movable elements of the punching and printing device, and FIGS. 1 and 2 represent the lowered position of link 20 and plate 23 in punching and printing. FIG. 1a shows the upper portions of the movable parts of the machine raised, as occurs when the lever 30 is moved to its broken line position of FIG. 1.

The bedplate 10 is provided with locating pins 34 and 35 adapted to extend into corresponding locating holes in a ticket section, and when a ticket section T is thus positioned the right end portion of the ticket section as shown in FIG. 2 will extend beneath the vertically movable parts of the punching and printing head. The parts that overlie the ticket are supported altogether from beyond the right end of the ticket, those parts which are vertically movable being carried by the link 20, and those parts which are stationary being supported from the bedplate 10. When the head is raised ticket material can be advanced either to the left or right in FIG. 1a, so that successive sections of a multiple section ticket can be brought into position to be punched and printed, or any particular section of a multiple section ticket can be positioned for punching and printing.

A bank of for example seventy-five punch pins 37 (in fifteen columns of five pins per column) may be provided. It will be understood that for many uses a lesser number of columns will be sufficient. Pins 37 are guided for vertical movement in stationary upper and lower retainer plates 38 and 39. As seen in FIG. 3, the lower stationary plate 39 is supported from the bedplate 10 by a spacer 40, the two plates 38 and 39 are separated by a spacer 41, and the stud 24 which guides the vertically movable plate 23 is threaded into the spacer 41.

Between the levels of the stationary retainer plates 38 and 39, a horizontally disposed and vertically movable pin lifter plate 45 surrounds the punch pins 37 beneath collars 37a thereon. Punch lifter plate 45 is vertically movable with the head, and in rising insures withdrawal of all pins which have penetrated a ticket, the lower ends of these pins withdrawing into the holes in the lower pin retainer plate 39 as in FIG. 1a, and thus being shielded. Plate 45 at its right end in FIG. 2 is secured to a shoulder on link 20 and at its opposite end is connected to a vertical end plate 46 that extends down from the plate 23.

A stationary die 47 is inset in the bedplate 10 beneath the punches. In the die 47, but offset from the field of punching, a printing platen 49 is provided. An ink ribbon 50 is guided, by suitable guide means including the guide 51, above the top of the upper plate 23, down the left side of the head in FIG. 2, thence to the right over the part of the ticket overlying the platen, the link 20 being slotted at 20a to provide a passage for the ribbon. Any suitable ribbon feeding and reversing mechanism, not shown, may be provided.

Removable interchangeable keys 60 are provided, each serving as a punch interposer for a selected combination of punch pins of a column and also carrying a printing character corresponding to the combination of punch pins operated by the key as an interposer.

As shown a key 60 has a vertically extending portion 60a from which an upper horizontal portion 60b extends, overlying the pins of one column. This upper portion 60a is notched so that it clears a predetermined three of the punch pins of the column and engages and operates the other predetermined two punch pins of the column.

As the head is lowered, the lowering of the pin lifter plate 45 allows the punch pins to move downwardly. Those pins which are cleared by the notched portions of keys, and any pins in columns where no key is present will simply rest on the ticket without penetrating it. Those pins which are operated by the keys will be driven through the ticket and into the die 47.

A lower horizontally extending portion 60c of the key

carries a type bar 61 carrying a downwardly-facing printing character, such as a digit, corresponding to the meaning of the punching which is effected by the two punch pins operated by the key.

With fifteen columns of punch pins, as many as fifteen keys may be provided each disposed with its notched portion 60a above a column of punch pins. For simplicity of illustration only two such keys are shown in FIG. 2.

For positioning the keys in the vertically movable head, the upper plate 23 is slotted at its lower face to receive the upper edge portions of the keys, and a vertically disposed lower guide plate 65 is slotted at its lower edge to receive the upper edge portions of the lower horizontal portions 60c of the keys. Lower guideplate 65 is slotted to receive a spring pressed detent 66 having a limited upward movement. This detent 66 urges the keys upwardly and also, when keys are fully inserted and their vertically extending portions 60a are seated against the guideplate 65, the detent 66 engages with shoulders 67 on the keys to retain them against accidental displacement to the right in FIG. 1. The upper portions of the keys, where they extend out from the head, are preferably notched, as at 68 (FIG. 1) to receive a bill or prong of a hand-tool 70 (FIG. 1a) by which the keys may be readily pulled out.

It will be understood that the code which systematically relates printing and punching for each of the removable and interchangeable keys will in most instances, although not necessarily, be the same as is employed in the initial printing and punching of the ticket. Thus where the tickets are originally manufactured by the machine of said Bone and Sloan patent, leaving space for further printing and punching by the machine of the present invention, the printing characters of the keys will advantageously be the ten digits and the code will be a combination code using the ten combinations of two punch positions out of five.

The keys, aside from their type bars, are sheet metal and accordingly are so inexpensive that each of a group of machines of the present may be supplied with a sufficient assortment of keys to enable the setting up of any number within the capacity of the machine. In many cases however it will be practicable for the users of a group of machines to draw their keys from a common supply.

The principal elements of the illustrated preferred form of movable head are: the upper part of link 20, the horizontal plate 23 at the top of link 20, the horizontal lifter plate 45, the vertical end plate 46 and the vertically disposed guide plate 65. The keys 60, as evident, partake of the movement of this head relative to the die and platen.

I claim:

1. A printing and punching machine including a head, a bank of punches arranged to cover a field of punching, a die for the punches, the head and die being adapted for relative movement of relative approach and relative withdrawal, a group of individually removable and interchangeable punch-controlling interposers of plate-like form adapted to be mounted in the head so as to partake of said relative movement, means for releasably holding the interposers in the head each aligned with a respective plurality of said punches which cover a column of said field, the punches being slidably mounted between the interposers and the die and the machine including means normally holding the punches spaced from the die, upon such relative withdrawal, said group of interposers presenting to predetermined punches of the bank lateral edge surfaces comprising punch-operating surfaces opposed to the die so that relative approach of the group of interposers and the die edgewise of the interposers will force said predetermined punches through sheet material at the die, means for causing relative movement between head and die to cause said relative approach, the individual interposers having combined therewith portions extending to the region of sheet material positioned to be punched

by the punches and there carrying respective printing characters having systematic correspondence to the punching by the respective column of punches with which the interposer is aligned, and a printing platen adapted to cooperate with said printing characters upon such relative approach of interposers and die.

2. A printing and punching machine including a head, a bank of punches arranged to cover a field of punching, a die for the punches, the head and die being adapted for relative movement of relative approach and relative withdrawal, a group of individually removable and interchangeable punch-controlling interposers of plate-like form adapted to be mounted in the head so as to partake of said relative movement, means for releasably holding the interposers in the head each aligned with a respective plurality of said punches which cover a column of said field, the punches being slidably mounted between the interposers and the die, said group of interposers presenting to predetermined punches of the bank lateral edge surfaces comprising punch-operating surfaces opposed to the die so that relative approach of the group of interposers and the die edgewise of the interposers will force said predetermined punches through sheet material at the die, means for causing relative movement between head and die to cause said relative approach and subsequent relative withdrawal of the interposers and die, the individual interposers having combined therewith portions extending to the region of sheet material positioned to be punched by the punches and there carrying respective printing characters having systematic correspondence to the punching by the respective column of punches with which the interposer is aligned, a printing platen adapted to cooperate with said printing characters upon such relative approach of interposers and die, means for separating the punches and die upon relative withdrawal of the interposers and die, and a plate having apertures for the punches, the operative ends of the punches withdrawing into said apertures when the punches and die are separated.

3. A printing and punching machine including a bank of punches arranged to cover a field of punching, removable and interchangeable sheet metal key members having upper portions extending laterally over the upper ends of punches of the bank for operating predetermined punches thereof and having lower portions extending laterally to-

- ward the bank of punches, the upper and lower laterally extending portions of each key member being integrally connected, and the lower laterally extending portion of each key member carrying a downwardly directed printing element, the machine including an upper guide presenting slots for the reception of upper edges of the upper laterally extending portions of the key members and a lower guide presenting slots for the reception of upper edges of the lower laterally extending portions of the key members, means for urging the key members upwardly, a bed including a die for the punches and a platen, a head carrying said upper and lower guides, and means for causing relative approach and withdrawal of the head and bed.
4. A machine for printing and punching sheet material comprising a die for supporting said material, a head above the die, punches for punching said material, the punches extending downwardly adjacent to the supported material, key members for operating the punches, means normally holding the punches in the head and spaced from the die and slidable on the head, means for mounting the key members on the head, and means for producing relative movement between the head and die, each key member comprising an integral sheet metal body including an upper portion and a lower portion, the upper portion constituting an upper lateral extension forming a punch-operating interposer and notched with downwardly open notching in the lower edge of the lateral extension to clear predetermined punches, a lower portion extending below said lower edge, and a printing element directed downwardly from the lower portion adjacent the supported material.
